UNITED STATES PATENT OFFICE.

JOHN W. NYSTROM, OF ST. PETERSBURG, RUSSIA.

APPARATUS FOR DOCKING SHIPS, &c.

Specification of Letters Patent No. 31,125, dated January 15, 1861.

To all whom it may concern:

Be it known that I, JOHN W. NYSTROM, a citizen of the United States of America, now residing at St. Petersburg, in the Empire 5 of Russia, have invented certain new and Improved Apparatus or Machinery for Docking Ships and other Vessels, for Carrying Large Vessels Over Shoals, and for Raising Sunken Vessels; and I do hereby 10 declare that the following is a full and clear and exact description of the same, reference being had to the accompanying drawings, forming part of this specification.

My improved apparatus or machinery 15 consists principally of one or more pontoons of novel character and construction, which are navigable, self-propelling and have within themselves the power of sinking and floating again under the control of persons 20 on board.

Figure 1, in the drawing, is a midship vertical section of one of my pontoons, showing also a stern view of a large steam-ship which is supposed to be docked on a number 25 of such pontoons. Fig. 2 is a plan of the same pontoon. Fig. 3 is a plan of the same exhibiting the interior in section. Fig. 4 exhibits a dock or camel composed of a number of such pontoons and carrying a 30 large steam-ship. Figs. 5 and 6 are views illustrating the operation of raising sunken vessels with these pontoons.

Similar letters of reference indicate corresponding parts in the several figures.

I will now proceed to describe the construction of a pontoon. It is in the form of a flat bottomed boat with a close deck with two upright towers A, A', which commence at the bottom as shown in Fig. 1, and extend to a considerable height above the deck. These towers A, A', are at a distance apart to admit between them the largest class of vessels for which the pontoon is to be employed, and the said towers are connected 40 below the deck D, of the pontoon by a corridor C, which runs along the centers of the pontoon, said corridor being wide enough to permit the passage through it of one or more persons. The towers and corridor are 45 shut off from the remainder of the hull of the vessel which is divided into a number of water-tight compartments B, B, which will be hereinafter spoken of as tanks, and which may be filled with water for the purpose of sinking the pontoon, and have the water pumped out again for the purpose of

floating it. The pontoon represented has twelve tanks. The towers A, A', serve a similar purpose to the balance tanks of what is known in the United States as the floating sectional dock; viz: that of keeping the pontoon at any required depth below the surface of the water, and besides this, one of them, the after one A, contains the pumps a, a, for pumping or forcing out the 60 water from the tanks, and the steam-engine b c d, for driving the pumps and the screw propeller e, and the other A', contains the boiler f, whose chimney f' passes up through the said tower and so does the pipe t, from 70 the safety valve. The two towers, being open at the top, are ventilated and serve to ventilate the corridor where the engineer is stationed for the purpose of managing the pontoons in accordance with commands given by a person stationed on a 75 railed platform at the top of either of the towers to direct the operation.

The several pipes for connecting the different parts of the apparatus are arranged 80 within the corridor, and the necessary cocks or at least the handles of them are all brought close together about midway between the towers so as to be all at once within the control of the engineer. The pipes, 85 cocks, or valves and their connections may be variously arranged so that it will only be necessary to give a general idea of how they are applied.

g, (Figs. 1 and 3), is the steam-pipe running 90 direct from the boiler to the engine.

h, is the feed-pipe for supplying the boiler.

i, is the suction-pipe of the pump running 95 to the engineer's station in the middle of the corridor, and having branching from it four pipes j, each connecting with three of the tanks, and having a separate cock k, to open and close it.

l, is an air-pipe passing the engine-tower B, to admit air to the tanks or allow it to 100 escape therefrom by four branches m, each branch connecting with three tanks and having a separate cock n, to open and close it. The air-pipe is also so connected with the pump that the latter may be used as an air forcing pump to force air through a pipe p, into the branches m, and through them into the tanks for the purpose of driving the water out at the bottom thereof, which may be necessary or desirable in some cases not 110 necessary to specify. Each tank may be provided with two valves, or a cock and a

valve, viz: a valve or cock r , operated by hand for letting in the water, and a valve s , opening outward by the pressure of the air, to permit the latter to force out the water.

- 5 Instead however of having every tank provided with the valves r and s , only four of them may be thus provided, and the tanks may be divided into four series with those of each series communicating with each other.

10 The pontoon may be built wholly of iron, which, all things considered, is the cheapest and safest material for the purpose. The steam-engine for pumping and propelling 15 should, preferably, be of the condensing kind, as in pumping out the tanks the water drawn from them may be employed for the condensation of the steam. The propeller should be capable of being uncoupled during 20 docking and lifting operations, and the propeller and pumping machinery generally so applied that either can be operated independently, or both simultaneously. The towers and the corridors are lighted by 25 small lights or windows u , u . The towers may have suitable ladders inside and outside to enable them to be descended by the persons employed on board.

30 In each tower are placed four truss-timbers y , which serve to keep a ship, or other vessel, in a proper position on the pontoons. These truss-timbers pass right through the towers; and each is surrounded inside of its tower by a square tube v , which is closely 35 secured to the sides of the tower to keep the water out when the timber is submerged. Each pontoon has four chock-blocks w , w , arranged in such manner as to be capable of being adjusted under the bottom of a vessel 40 under which the pontoon is placed, such chocks being operated by blocks and tackles. Each pontoon is furnished on deck with two windlasses G , G' , one near the stem and the other near the stern. The pontoons may be 45 fitted with sails to aid them in voyaging from place to place.

The pontoon may be ballasted by the admission of a suitable quantity of water into its tanks to give it such a draft of water as 50 may be best for its propulsion and navigation from place to place, say to the line x , x , Fig. 1. When it is to be lowered the engineer opens the cocks or valves r , to let water into the tanks, and when it begins to sink 55 and the air in the tanks becomes compressed he opens the cocks n , sufficiently for the escape of air fast enough to permit the gradual descent of the pontoon, and if it descends faster on one side or end its descent can be 60 corrected by giving more or less opening to the proper air-cock as soon as the fault is discovered by the glass-gages z , (Fig. 1). The pontoon may be sunk nearly to the top of the towers, or if pipes are secured by 65 water-tight connections with the contracted

open mouths of the towers it may be sunk still deeper.

When the pontoon is to be raised there are several circumstances to be considered, viz: if it is to lift uniformly all over, or if it is 70 to lift only with one end, or only with one side, and accordingly the engineer opens all or only a portion of the cocks and the pumps are set to work to expel or extract the water from the whole of the tanks or only from 75 those on one side, or from those nearest one end.

The operation of docking a ship is as follows: The form of the bottom of the ship having been ascertained as nearly as practicable, in order that chock-blocks of suitable form may be placed on the pontoons, a sufficient number of pontoons are arranged side by side, as shown at F , F , in Fig. 4, and connected together by suitable lines. The 80 chock-blocks being placed as nearly as possible in proper positions the pontoons are at a given command, caused to commence sinking. Care should be taken by conductors stationed at the tops of the towers to direct 85 the engineers that all the pontoons sink together. When the pontoons are sunk sufficiently deep, the ship S , Figs. 1 and 4, is propelled, towed, or hauled in between their towers A , A , and is adjusted midway between the latter by the truss-timbers y ; after which the pontoons are all carefully raised till they touch the keel of the ship, when the pumps are stopped, and the chock-blocks drawn tight under the ship's bottom by the 100 tackles provided for the purpose. The truss-timbers y , are now secured to the sides of the ship, and the pumps set in motion again, and the pontoon-dock commences to rise with the ship upon it, till the latter is lifted 105 out of the water, and the decks of the pontoons are just above the surface of the water. A precisely similar system of pontoons may be employed as a self-propelling camel for carrying large vessels over shoals or taking 110 them into shallow harbors to discharge and receive cargoes.

The operation of raising a sunken vessel, illustrated in Figs. 5 and 6, is as follows: The location of the vessel having been ascertained a number of men in diving-dresses are sent down to make a sufficient number of lines fast to the shrouds or other convenient part of the vessel, and this having been done the divers ascend and the other ends of the 115 lines are made fast to a sufficient number of pontoons to raise the vessel, said lines being led over blocks and sheaves to the two capstans of each pontoon and secured thereto. The pontoons are then lowered till their 120 decks are level with the water, and a new hold taken by the lines on the capstans. A suitable number of men in diving-dresses are then placed at each capstan to keep the lines as tight as possible while the pontoons are 125 130

being lowered to the required depth. The lines having been secured to the capstans with pawls, the men can ascend to the top of the towers and the engine can be set in operation to pump the water out of the tanks. In this way the vessel will be raised a considerable distance, and then by setting the propellers of the pontoons in operation it may be carried into shallower water where it will rest on the bottom. The same operation may be repeated as often as necessary till the vessel is deposited in quite shallow water, when it may be raised by slings 7, applied, as shown in Fig. 6, in connection with pontoons arranged alongside till it is high enough to have its bottom inspected and any hole plugged up or closed up, that the water may be pumped out of it by the pontoon pumps and the ship floated, when it may be docked by the pontoons, as before described. In the slinging operation, illus-

trated in Fig. 6, it may be found necessary to pump the water out of the tanks on but one side of each pontoon.

I do not claim broadly the invention of floats or pontoons that are sunk by the admission of water and raised by the expulsion of the water, but

What I claim as my invention, and desire to secure by Letters Patent, is:—

1. The construction of pontoons with communicating towers and corridors arranged and operating substantially as and for the purpose herein specified.

2. The combination with such pontoons of pumping and propelling machinery capable of operating together or independently, substantially as herein described.

JOHN W. NYSTROM.
